UNITED STATES PATENT OFFICE.

CHARLES B. KENYON, OF GREENWICH, NEW YORK.

INCUBATOR.

SPECIFICATION forming part of Letters Patent No. 735,885, dated August 11, 1903.

Application filed April 23, 1903. Serial No. 154,011. (No model.)

To all whom it may concern:

Be it known that I, CHARLES B. KENYON, a citizen of the United States, residing at Greenwich, in the county of Washington and State of New York, have invented certain new and useful Improvements in Incubators; and I do declare the following to be a full, clear, and exact description of the invention, such as will enable others skilled in the art to which it appertains to make and use the same.

This invention relates to improvements in incubators.

The object of the invention is to construct an incubator in which an even distribution of the heat and a perfect ventilation is provided for.

A further object is to provide an incubator which will be simple in construction and operation, comparatively inexpensive of production, and the arrangement and operation of the parts being such as to closely simulate the natural method of egg-hatching.

With these and other objects in view the invention consists of certain novel features of construction, combination, and arrangement of parts, as will be more fully described, and particularly pointed out in the appended claims.

Figure 1 is a longitudinal vertical sectional view of the incubator. Fig. 2 is a vertical cross-sectional view. Fig. 3 is a horizontal sectional view of the same. Fig. 4 is a detail side elevation of the outside heat-flues. Fig. 5 is a detail view of the egg-tray.

In the drawings, 1 denotes the body of the incubator comprising an outer wall or casing 2 and an inner wall 3, spaced apart on all sides except the bottom to form a dead-air compartment 3^a, which entirely surrounds the inner wall except at the bottom, as stated, and at the lower portion of one end of the casing, as hereinafter described.

4 denotes the egg-tray, arranged near the bottom of the incubator and supported upon cleats 5, fixed to the inner wall 3. In the construction of the egg-tray an open frame 6 is provided, and to said frame is connected the edges of a coarse-wire screen 7, the screen being formed so as to slope on all sides toward the center to simulate the form of a hen's nest.

Above the egg-tray and about midway be-

tween the same and the top of the incubator is arranged a frame 8, constructed to incline from the sides of the incubator toward the center in a substantially V form, and over said frame is stretched a covering of flannel or similar material forming a partition or diaphragm 9, the object of which is to hold the heat above the eggs in the tray 4 and permit the same to slowly pass downwardly through the flannel to the lower part of the incubator. After passing through the flannel diaphragm 9 the heated air is retarded in its further downward flow by the V-shaped frame 8, which guides it toward the center, from which as it passes downward it flows outwardly, so as to cover the entire area of the egg-tray 6. By the use of this retarder and deflector the heat passes downward and is spread to the several eggs on the tray in a natural manner and the natural process of incubation further simulated.

Below the egg-tray and near the bottom of the incubator is arranged a frame 10, covered with a fine-mesh wire-netting, forming a screen or diaphragm 12. The object of this screen is to retard the passage of the heat to the ventilators in the bottom of the incubator and prevent undue drafts.

13 denotes a ventilating-chamber arranged between the inner and outer walls at one end of the incubator, and 14 denotes flues or pipes arranged upon the bottom of the incubator, one end of which communicates with the chamber 13 and the opposite ends of which open into the bottom of the egg-chamber of the incubator, as shown. As shown, the said chamber 13 is cut off by strips 13', arranged between the inner and outer walls 2 and 3 from the dead-air space 3^a.

15 denotes a vent arranged in the bottom of the incubator and is adapted to be closed by a plate 16, which is adapted to slide in ways 17, formed on a plate 18, having a hole formed therein, said plate being arranged upon the bottom of the incubator in such manner that the hole therein coincides with the vent-hole 15 in the bottom of the incubator.

19 denotes a heat-conducting flue arranged at one end of the incubator, near the upper end of which is formed a laterally-projecting branch pipe or flue 20, which is adapted to en-

ter the incubator above the flannel partition 9. Within the branch pipe 20 is arranged a horizontally-disposed plate 21, which extends partly across the flue 19, as shown. The plate 5 21 serves as a baffle-plate and causes a circulation or breaks the flow of heat from the flue to the incubator.

22 denotes a thimble or ferrule arranged upon and surrounding the branch pipe 20, 10 and between said pipe and the thimble is placed a packing of asbestos or other protective material 23, the object of which is to prevent overheating of the woodwork of the incubator where the branch pipe 20 enters the 15 same.

24 denotes a hood or bell which is adapted to surround and to be supported upon the flue 19 near the lower end of the incubator. 25 denotes a branch pipe projecting laterally from 20 the hood or bell 24, the pipe 25 entering the ventilating-chamber 13 of the incubator and being provided with a surrounding packing and thimble 26 and 27, similar to the arrangement on the pipe 20. An annular series of 25 holes 28 is formed in the upper portion of the hood 24, the object of which is to permit the escape of the heat at this point.

29 denotes a shelf or bracket arranged beneath the lower end of the flue 19, being supported in this position by means of an inclined arm 30, having a pivotal connection at its upper end with the under side of the incubator. The shelf is further supported by means of a wire 31, fastened at its upper end 35 to the incubator and connected at its lower end to the lower end of the arm 30. This method of supporting the shelf permits the same to be swung to one side to allow the lamp-chimney to be inserted in the lower end 40 of the flue, the shelf being then swung back to support the lamp.

32 denotes the usual damper mechanism arranged on the top of the incubator and automatically controlled by the thermostat 33, arranged within the incubator, as shown.

In operating the incubator the eggs are arranged in the hollow of the egg-tray after the manner of the eggs in a hen's nest, the large volume of heat that is held above the same 50 by the flannel partition or diaphragm and allowed to slowly pass through the same to the eggs simulating the warmth from the hen's body when covering the eggs, a perfect circulation of the air being provided for through 55 the ventilating-flues 14, chamber 13, and hood 24.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 60 this invention.

Having thus fully described my invention, what I claim, and desire to secure by Letters Patent, is—

1. In an incubator, the combination with a 70 casing having an egg-tray supported therein, of a fabric partition or diaphragm arranged above said egg-tray, means for supplying heated air to the incubator above said fabric diaphragm, means for directing the hot air 75 from said fabric diaphragm to the center of the incubating-chamber above the egg-tray, and means for permitting the air to escape more or less slowly from beneath said screen or diaphragm located below said egg-tray, 80 substantially as described.

2. In an incubator, the combination with a suitable box or casing of an egg-tray supported in said casing, a fabric partition or diaphragm arranged above said egg-tray, and 85 a screen or diaphragm arranged below said egg-tray, a hot-air flue arranged at one end of said incubator, a branch pipe connecting said hot-air flue with said incubator above said fabric diaphragm, a ventilating-chamber 90 arranged in one end of said casing, ventilating-flues connecting said chamber with the interior of the incubator beneath said screen or diaphragm, a hood or bell arranged upon said hot-air flue, and means for connecting 95 said ventilating-chamber with said hood or bell, substantially as described.

3. In an incubator, the combination with a suitable box or casing of an egg-tray arranged in said casing, said tray comprising 100 an open frame covered with a coarse-wire netting sloping in all directions toward the center to form a hollow nest-like receptacle, a fabric diaphragm arranged above said egg-tray, and a screen-diaphragm arranged below 105 said egg-tray, means for directing hot air into the incubator above said fabric diaphragm, and ventilating-flues and a fresh-air vent arranged beneath said screen-diaphragm and means for regulating the size of said fresh-air 110 vent, substantially as described.

4. In an incubator, the combination with a casing having an egg-tray supported therein, of a fabric partition or diaphragm arranged above said egg-tray, a screen or diaphragm 115 arranged below said egg-tray, means for supplying the incubator with hot air above said fabric diaphragm, and a ventilating-chamber formed between the side walls of the casing and having an inlet communicating directly 120 with the incubator below the screen or diaphragm underneath the egg-tray and an outlet communicating with the atmosphere.

5. In an incubator, the combination with a casing having an egg-tray supported therein, 125 of a fabric partition or diaphragm arranged above said egg-tray, a screen or diaphragm arranged below said egg-tray, means for supplying the incubator with hot air above said diaphragm, said means including a flue disposed upon the side of the incubator, a ventilating-chamber disposed at the side of the 130

casing adjacent to said flue and in communication with the incubator below the screen or diaphragm underneath the egg-tray, a hood or bell mounted upon said flue, and a flue connecting said hood or bell with the ventilating chamber, substantially as described.

5 In testimony whereof I have hereunto set

my hand in presence of two subscribing witnesses.

CHARLES B. KENYON.
